UNITED STATES PATENT OFFICE.

GEORGE R. COOK, OF CARROLLTON, GEORGIA, ASSIGNOR OF ONE-HALF TO ALONZO O. TURNER AND ONE-HALF TO JAMES B. F. DIAL, BOTH OF CARROLLTON, GEORGIA.

ROAD SCRAPING, GRADING, AND DITCHING MACHINE.

1,374,824.

Specification of Letters Patent. Patented Apr. 12, 1921.

Application filed August 2, 1919. Serial No. 314,846.

To all whom it may concern:

Be it known that I, GEORGE R. COOK, a citizen of the United States, residing at Carrollton, in the county of Carroll and State 5 of Georgia, have invented new and useful Improvements in Road Scraping, Grading, and Ditching Machines, of which the following is a specification.

This invention relates to road scraping, 10 grading and ditching machines, and consists essentially of features of improvement based on the structure of the machine disclosed by my Patent No. 1,265,702, dated May 7, 1918, and which will be more fully herein- 15 after described and claimed.

The main object of the invention is to generally improve this particular type of machine in such manner as to more effectively perform the operations of road scraping, 20 grading and ditching; to increase the strength and durability of the machine and provide for a more convenient and expeditious assemblage of the parts, particularly those connecting the share or blade and the 25 runner or slide. A further object of the invention is to provide an adjustable attachment in connection with the rear end of the share or mold board for the purpose of making said share or mold board quickly 30 shed dirt or soil and also to facilitate the formation of terraces of any shape and dimensions desired.

In the drawings:—

Figure 1 is a perspective view of a machine embodying the features of the invention.

Fig. 2 is a top plan view of the improved machine.

Fig. 3 is a transverse vertical section taken 40 in the plane of the line 3—3, Fig. 2.

Fig. 4 is a transverse vertical section taken 45 in the plane of the line 4—4, Fig. 2.

Fig. 5 is a detail perspective view of a part of the machine showing a modification 50 of the structure.

As in my patented machine hereinbefore mentioned, the essential components of the improved machine are a share or blade 5 which serves as a mold board, a runner or 50 slide 6 and a draft bar 7. The share or mold board 5 has a concavo-convex contour in cross section with the concave side 8 outside. This share or mold board 5 has upper and lower similar straight edges 9 and 10

and also upper and lower points 11 and 12 55 which are adapted to serve as cutting means and project beyond or in advance of the front end of the share or mold board with an intervening clear space 13 between them, the said points 11 and 12 being concavo-convex in cross sectional contour and removably bolted to the mold board, as at 14. The slide 6 is vertically straight with upper and lower similar longitudinally straight working edges 15 and 16. The front end of the 60 slide is rolled to form knuckles or cuffs 17 which are disposed between upper and lower angle brackets 18 secured to the inner side of the front extremity of the mold board 5, and extending through the said brackets 18 65 and knuckles or cuffs 17 is a pintle bolt 19 to form a hinge connection between the front ends of the mold board and slide. By means of the hinge connection just explained the mold board 5 may be adjusted as desired 70 relatively to the slide 6, and to maintain the adjustment of the mold board the inner side of the slide has a longitudinally disposed keeper bar 20 secured thereto by angle brackets 21, said bar being provided with a 75 plurality of openings 22 therein to adjustably receive a coupling bolt 23 inserted through the end of a connecting rod or bar 24 which is attached to the slide 6 in a 80 manner presently explained.

The draft bar 7 preferably consists of a flat strip of suitable length and thickness formed with a plurality of holes 25 for adjustable attachment thereto of draft means by which the machine is pulled or drawn 85 as desired. The inner end of the draft bar has a knuckle or cuff 26 which is attached to the center of the pintle-bolt 19 between the knuckles or cuffs 18 at the front end of the slide 6. The bar 7 extends horizontally outward from the pintle bolt 19, or the front hinged ends of the mold board and slide, and to the outer end thereof a draft rod 27 is secured and extends rearwardly and curves 90 around and at a distance from the rear end 100 of the mold board 5 and then projects forwardly and inwardly toward and secured to the said mold board in a preferred particular manner. The rod 27 fully clears the outer concave working side of the mold board 5 as well as the rear end of the latter 105 and does not in the least interfere with the movement of the dirt or soil over the mold

board. The draft rod 27 transmits the draft pull to and operates to steady the mold board and reliably and positively holds the same up to the work, and thereby an advantageous guiding and truing action ensues when a cut is made by the cutting points 11 and 12.

One of the special features of improvement consists of an arch or bridge bracket 28 secured to and extending vertically relatively to the inner side of the mold board 5. The end of the connecting rod or bar 24 opposite that adjustably engaging the keeper bar 20 is bifurcated or formed with a fork 29, and the members of this fork respectively partially embrace and are pivoted to the members of the bracket 28 and are free to move on the latter which serves as a fulcrum projection. The draft rod 27 extends 10 through the fork 29 and is preferably secured to the center or apex of the bridge or arch bracket 28 by a suitable clip or analogous device 30, the said rod 27 continuing in advance of the bracket 28 and riveted or 15 bolted to the mold board 5 as at 31. This particular attached association of the rod 27 with the mold board 5 results in an effective distribution of the sustaining and draft functions of the said rod relatively to the 20 mold board.

A further special feature of improvement in the present machine consists of an adjustable wheel or roller attachment at the rear extremity of the mold board 5 to facilitate shedding of dirt or soil by said board and provide for the formation of terraces of any shape desired, either high or low and narrow or wide. This attachment comprises a vertical guide 32 secured to the mold board 5 and having upper and lower set screws 33. Slidably mounted in the guide 32 are two reversely arranged shanks or stems 34 and 35 respectively carrying a wheel or roller 36 and 37 to project above and below the 30 upper and lower edges of the mold board. By loosening the adjusting screws 33 the shanks or stems 34 and 35 with their wheels or rollers 36 and 37 may be raised or lowered and set in the adjusted position desired by 35 tightening the said screws.

The improved machine may be overturned or reversed bodily by detaching the draft means from the bar 7 and subsequently reattaching the said draft means to the bar. 40 This provision for reversible use of the machine will permit operation thereof without requiring turning movements of the machine, as both points 11 and 12, the upper and lower edges of the mold board 5 and runner 6 and the reversely arranged wheels or rollers 36 and 37 are equally serviceable in performing their intended functions, and thereby the wearing qualities of the machine are rendered more durable. The machine 45 is also capable of being turned similar to or-

inary scraping, grading and ditching machines without overturning the same in performing certain work therewith.

In the modified construction shown by Fig. 5, the wheels or rollers 36 and 37 and the devices adjustably carrying the same are replaced by drags 38 and 39 which consist of narrow strips secured to the share or blade adjacent to the upper and lower edges of the latter, the said strips curving outwardly from the share or blade edges and having a slight yielding action. These drags operate similarly to the wheels or rollers, or, have a like function.

What is claimed as new is:—

1. A road scraping, grading and ditching machine comprising a mold board provided with upper and lower cutting points at its front end and with a bridge bracket at the inner side of its rear end, a slide hinged at 85 its front end to the similar end of the mold board, the mold board and slide both having upper and lower working edges to render the same reversible, a draft bar connected to the front extremities of the mold board 90 and slide, and a draft rod secured to the outer end of the draft bar and extending around the rear end of the mold board and secured to the said bridge bracket and the mold board in advance of the bracket. 95

2. A road scraping, grading and ditching machine comprising a mold board provided with upper and lower cutting points at its front end and with a bridge bracket at the inner side of its rear end, a slide hinged at 100 its front end to the similar end of the mold board, the mold board and slide both having upper and lower working edges to render the same reversible, a longitudinal keeper bar secured to the inner side of the slide, a connecting rod having a bifurcated end pivoted to the bridge bracket and adjustably attached to the keeper bar, a draft bar connected to the front extremities of the mold board and slide, and a draft rod 105 secured to the draft bar and extending around the rear end of the mold board and through the bifurcated end of the connecting rod, the draft rod being secured to the bridge bracket. 110

3. A road scraping, grading and ditching machine comprising a mold board provided with upper and lower cutting points at its front end and with a bridge bracket at the inner side of its rear end, a slide hinged 115 at its front end to the similar end of the mold board, the mold board and slide both having upper and lower working edges to render the same reversible, a longitudinal keeper bar secured to the inner side of the slide, a connecting rod having a bifurcated end pivoted to the bridge bracket and adjustably attached to the keeper bar, a draft bar connected to the front extremities of the mold board and slide, and a draft rod se- 120 125 130

cured to the outer end of the draft bar and extending around the rear end of the mold board and secured to the said bridge bracket and the mold board in advance of the 5 bracket.

4. A road scraping, grading and ditching machine, comprising a mold board provided with upper and lower cutting points at the front end and upper and lower cutting 10 edges extending fully from the front to the rear thereof to render the same reversible, a slide hinged at its front end to the front end of the mold board and also having upper and lower working edges to render the 15 same reversible, means adjustably connecting the said mold board and slide, the inner side of the rear extremity of the mold board being provided with a bracket, and vertically disposed stems reversely and adjustably 20 engaging the said bracket and having wheels in their opposite ends projecting above and below the upper and lower edges of the mold board, each wheel and its stem being adjustable independently of the remaining 25 wheel and stem to vary the projections of the wheels above and below the upper and lower edges of the mold board, the machine being bodily overturned in reversing the same without detaching or reversing the mold board or slide.

5. A road scraping, grading and ditching machine comprising a mold board provided with upper and lower cutting points at its front end and with a bridge bracket at the 30 inner side of its rear end, a slide hinged at its front end to the similar end of the mold board, the mold board and slide both having upper and lower working edges to

render the same reversible, upper and lower vertically adjustable wheels at the inner side 40 of the rear extremity of said mold board, a draft bar connected to the front extremities of the mold board and slide, and a draft rod secured to the outer end of the draft bar and extending around the rear end of 45 the mold board and secured to the said bridge bracket and the mold board in advance of the bracket.

6. A road scraping, grading and ditching machine, comprising a mold board having 50 upper and lower cutting points at its front end and also provided with upper and lower cutting edges extending the full length thereof, a slide hinged at its front end to the similar end of the mold board and also 55 having upper and lower working edges extending the full length thereof, and means carried by the mold board at the rear extremity of the latter and having uniform projection above and below the upper and 60 lower cutting edges of the mold board for instant use and service without adjustment when the machine is reversed by bodily overturning the same to facilitate shedding of dirt by the mold board and provide for 65 the formation of terraces without requiring rearrangement and readjustment of any part of the machine.

In testimony whereof I have hereunto set my hand in presence of two subscribing 70 witnesses.

GEORGE R. COOK.
